CLAIM

The ornamental design for a "Purse," as shown and described.

DESCRIPTION

FIG. 1 is a front elevational view of a "Purse," showing my new design, with both the front and rear elevational views being identical, and the broken-line showing of letters and numerals being merely exemplary of some superficial ornamentation;

FIG. 2 is a top plan view thereof;

FIG. 3 is a bottom plan view thereof;

FIG. 4 is a right side elevational view thereof; and,

FIG. 5 is a left side elevational view thereof.
